United States Patent Office

Des. 185,085
Patented May 5, 1959

185,085

SPOON OR SIMILAR ARTICLE

Kae E. Jones, New York, N.Y., assignor to Welling Ware,
Inc., New York, N.Y., a corporation of New York

Application April 17, 1958, Serial No. 50,503

Term of patent 7 years

(Cl. D54—12)

Fig. 1 is a top plan view of a spoon or similar article, showing my new design.

Fig. 2 is a side view thereof.

Fig. 3 is a bottom plan view thereof.

Fig. 4 is a sectional view taken on line 4—4 of Fig. 1.

Fig. 5 is a sectional view taken on line 5—5 of Fig. 1.

I claim:

The ornamental design for a spoon or similar article, substantially as shown.
